SAMUEL R. WILMOT, OF BROOKLYN, NEW YORK.

IMPROVEMENT IN APPARATUS FOR CLASPING SKIRTS.

Specification forming part of Letters Patent No. 37,992, dated March 24, 1863.

To all whom it may concern:

Be it known that I, SAMUEL R. WILMOT, of Brooklyn, in the county of Kings and the State of New York, have invented a new and useful Improvement in Machines for Applying Clasps to Hoops and Tapes in the Manufacture of Hoop Skirts; and I do hereby declare that the following is a full and exact description thereof, reference being had to the accompanying drawings, forming part of this specification, in which—

Figure 1 is a side elevation. Fig. 2 is the front elevation. Fig. 3 is the plan view. Fig. 4 is a cross-section of a portion on the line S S in Figs. 1 and 3. Figs. 5 and 6 are two separate cross sections of certain portions, Fig. 5 on the line T T and Fig. 6 on the line U U, both seen from a point in front. Fig. 7 is a perspective view of a clasp made somewhat larger than those usually employed. Figs. 8 and 9 are sections of a hoop and tape of a woven skeleton skirt; Fig. 8, a section before the clasp is applied, and Fig. 9 a section after the clasp has been strongly secured by my machine. Fig. 10 is a side elevation, and Figs. 11 and 12 are sections of certain parts of my machine, (full size.) Fig. 10 shows the hammer elevated, the black lines showing it in its highest position and the red lines showing it after it has descended a little and is commencing to give a corresponding motion to the clasp. Fig. 11 shows the hammer after it has descended so that the points of the clasp commence to penetrate the tape, and in red lines after the hammer has descended to its lowest position. Fig. 11 is a section on the line VV in Fig. 12, and Fig. 12 is a section of the hammer and its connections on the line W W in Fig. 11.

Similar letters of reference indicate like parts in all the figures.

In the use of my machine the hoops and tapes may be previously applied together and slightly secured in any approved manner, or they may be applied together at the moment, as may be most convenient. I prefer, however, to employ that species of tape in which loops are woven, adapted to produce what are known as "woven skeleton skirts," and to properly place the hoops therein beforehand. They may be secured slightly with gum or not, as may be deemed expedient. The machine by a single operation of the foot receives

a clasp from a suitable channel and inserts it and secures it in the skirt.

To enable others skilled in the art to make use of my invention, I will proceed to describe its construction and operation by the aid of the drawings and of the letters of reference marked thereon.

A is a casting, of the form represented secured upon a table or bench, a.

B is a stout lever, mounted on a fixed fulcrum C, and adapted to be operated by a treadle and suitable connections in a manner which will be readily understood. On the outer or front end of the lever B is a hammer, b, formed as represented, and having a face a little larger than the back of a clasp. This hammer b is slightly curved, forming an arc of which U is the center.

D is a die, hollowed as represented and adapted both to properly support the hoop and tape to be clasped together and to bend the points of the clasps inward thereupon, or, in other words, to clinch the points of the clasps. The die D is adjustable by screws in the manner represented.

E is a shallow spiral receptacle, in which the clasps are deposited in a confused mass, and from which they are supplied to the working part of the machine in regular succession and in a uniform position by the means now about to be described. The receptacle or reservoir E is slightly inclined, its open side being lowest. The opening connects with an inclined channel or connecting-plate, e, so arranged that the gravity of the clasps tends to induce a gentle and gradual movement or constant flow of the clasps from the open side of the reservoir E upon and along the neck e. The concussion of the entire machine by the clinching of the clasps between the hammer b and the die D is transmitted to the reservoir E and the neck e, leading therefrom, and slightly throws up the clasps at each operation of the machine. This shock throws the clasps upon their backs, and their gravity, aided by the continued succession of shocks, moves them in this condition along the inclined neck e. F is a lip or guiding surface, held at a sufficient height above e to act against the prongs of the clasps, leaving a space, f, between itself and e sufficient for the free admission of a portion of the body of the clasp. The neck e is so inclined as to bring

the clasps against the lip F and allow them to rub along it, and the friction of either presented prong against the lip F induces a rolling or turning of the clasp until both its prongs are in contact with the lip. In this position the clasp will slide along without further turning until it enters between the lip F and the corresponding shorter lip, G. This latter has, like the lip F, a space beneath it a little thicker than the body of the clasp. This opening is designated as g, and the space between the lip F and the lip G is but little greater than the width of the prongs of the clasp, so that when once in the channel M, between these lips F and G, the clasp is no longer at liberty to turn or move in any manner, except to slide steadily forward as it may be allowed by the gradual removal and consumption of its predecessors. This channel M is curved, as represented, and is adapted to deliver the clasps with their points downward ready for insertion in the tape in the most favorable condition both for the successful performance of the work and for the easy and continuous inspection by the eye of the operator. The extent of the motion of the lever B is sufficient to lift the working-face of the hammer b slightly above the back of the clasp, so that at each elevation of the hammer a clasp is thrown inward by the gravity of itself and of its successors from the lower end of the curved channel M. It is thrown immediately under and very nearly in contact with the face of the hammer b, which is destined to drive it downward into its place. The gravity of the clasp would induce its fall immediately whether the hammer acted or not, except for a supporting-piece, I, which is provided, and which is carried with the hammer, and requires a very careful description. The two useful portions of this supporting-piece are designated i i. The space between these portions is designated M', and is of just sufficient depth and width to allow one clasp to be contained, with its prongs presented downward, in the space M', and with its body supported at each side upon the surfaces i i. The main body of this supporting-piece is perforated by a large rectangular slot, J, in which the hammer b is allowed a slight vertical movement, as will be hereinafter explained.

K K are two slight projections near the upper end of this supporting-piece I, and L L are larger projections at or near the center of its length. These projections K and L perform important offices in imparting proper motions to the surfaces i i. Their forms and positions are correctly denoted in the drawings, as also the form of the entire supporting-piece I, which is made from one piece of steel or other hard and durable material.

P is a bent spring inserted in the manner represented between the supporting-piece and a broad shoulder, B', on the lever B. This spring urges both ends of the supporting-piece I outward, as is obvious. The face K' L' of the casting A, in the immediate vicinity of this

supporting-piece, is lined with steel, and is recessed to correspond with the projections K K and L L. This connection of the supporting-piece I to the hammer b, as described, compels the supporting-piece to rise and sink with each reciprocation of the hammer, but allows it to move up and down to a small extent independently thereof, or, rather, it allows the hammer b at each change in the direction of its motion to move up or down about one thirty-second part of an inch before the supporting-piece receives corresponding motion in the same direction. This dragging behind of the supporting-piece as it accompanies the lever B in its vibrations is due to the friction and the resistance produced by the projections K K dropping into the recesses K' K', and this dragging behind performs the important function of opening the space between the surfaces i i and the hammer b at each ascent of the latter, so that a clasp may freely enter when the hammer is up, and of contracting the space so as to embrace the clasp and hold and carry it steadily so soon as the hammer b commences to descend. When the hammer b has descended so far that the points of the clasp have penetrated the tape and commenced to meet and be deflected inward by the surface of the die D, a rapid backward or inward motion of the lower end of the supporting-piece I is produced by the contact of the lower inclined surfaces of the projections L L against the corresponding inclined surfaces L' L'. This sudden lateral motion of the supporting-piece is sufficient to entirely remove the parts i i from the action of the hammer b without touching either the die D or the tape lying thereon, causing the entire supporting-piece to stand in the position represented in the red outline in Fig. 11, and the hammer b, continuing its downward motion, produces its full effect in clinching the clasps. On the commencement of the return movement of the hammer b, after it has arisen about one thirty-second part of an inch it commences by its contact with the top of the slot J to raise the supporting-piece I, which immediately moves outward again to its proper position under the influence of the spring P, and it commences to receive and support another clasp so soon as the lower end of the hammer b rises above the mouth of the channel M. In case the friction and weight of the supporting-piece I is not sufficient to retard it and open the space to receive the clasp during the early part of the ascent of the hammer, the supporting-piece I is, by the contact of its upper end against the fixed surface a, compelled to stop when it has reached its proper place to stand, and thus the opening to receive the clasp is certain to be produced by the last portion of the upward movement of the hammer b. While this is progressing the operator has changed the position of the work, removing the joint of the hoop which has been clasped by the operation just described and presenting a new one, after which another movement of the treadle brings down the ham-

mer *b* with a fresh clasp and inserting and clinching it as before. Thus the operation is continued with great rapidity and with uniform and satisfactory results.

In commencing to operate my machine the attendant supplies a quantity of clasps to the reservoir *E*, and moves the treadle for a few seconds, until, by the jarring of the machine, a number of the clasps have ranged themselves in proper order against the lip *F* and have commenced to descend between it and the lip *G*, ready to be presented to the hammer *b*. She then seizes a hoop of the skirt and holds it in the proper position on the die *D*, and proceeds as described. When the skirt is finished, or when, for any other reason, the operation temporarily stops, the flow of clasps also stops, because the latter depends at its head on the concussion of the machine and because the passage *M* is barred at its lower end by the curved exterior surface of the hammer *b*, so that a clasp cannot escape except when *b* is in its highest position.

I have found in practice that the concussion due to the operation of my machine in the manner represented is not only sufficient to properly agitate the clasps and throw them on their backs, but is liable to be excessive and to induce too great a jumping motion. This excess of motion is probably due to the peculiar condition of the parts *E* and *e*, the same being supported at the points *e'* and *O* and bridging across the interval between these points in a slightly-arched condition. The concussion of the machine is liable to be so great as to reverse this arch or to cause the parts to act like an exceedingly flexible spring-board, so as to occasionally throw the clasps to a height far beyond that required. I find that the clasps are liable to thus jump at and near the center of this arch or spring-board far more than at the ends, showing that the concussion of the machine is not only felt there but is by the peculiar conditions liable to be at times very much magnified in the extent or rapidity of its motion. A post or the like firm support under the center of the arch might be sufficient to remedy the evil; but, as I wish to be able when I choose, to adjust the inclination of *E* and *e*, I prefer to make the support adjustable in some manner. A screw or the like may be employed here, but its adjustment involves some labor. To avoid this, and to insure uniformity and smoothness in the motion, I insert a mass of rubber, *N*, within the partial case *n* and find the result very satisfactory. There is always a possibility that a clasp, either slightly deformed or accidentally misplaced, may arrive near the commencement of the channel *M* in a false position. To avoid the presentation of such to the space *M*, I make the inclined neck or supporting-surface *e* very narrow for a short distance, *e'*, above the upper end of the lip *G*. If a clasp is moving in a correct position—*i. e.*, bearing properly with both its prongs against the lip *F*, and consequently with part of its body un-

der this lip, or in the space *f*—it will be supported by this narrow part of the neck *e* and will travel along, as described; but if any clasp be improperly placed or very seriously deformed, it will by its gravity alone fall off the unsupported side to be received in any suitable receptacle below. The effect is to present the clasps always in the right position to the upper extremity of the channel *M*, allowing each to hurry forward until it rests upon its predecessor, and to deliver them in single file as they are wanted at the lower end of the channel *M* in the manner described. In case the clasps do not come down the neck *e* with sufficient rapidity, or in case they come too fast so as to overflow the inclosed passage *M*, they may be hastened or checked near their exit from the spiral reservoir *E* by an occasional touch with the fingers of the attendant. The rapidity or freedom with which the clasps are delivered from the reservoir *E* depends somewhat upon the degree of inclination which is given to the neck *e*, through which they are delivered. This inclination may be increased or diminished by changing the form of the parts or by adjusting slightly the upright *O*, which is bolted to the casting *A* by bolts *Q*, passing through slots. This may allow adjustment to any extent which may be desired by simply slackening the bolts *Q*, raising or lowering the rod *O*, and consequently changing the inclination of *E* and *e*, and then again securing the bolts *Q*.

I am not necessarily confined to the several details of my invention represented, as such may be very greatly modified and still produce most of the good effects due to my invention.

Instead of curving the inclosed passage *M*, as represented, in order to reverse the position of the clasps while conducting them from *e* to the clinching device, I can twist the passage *M*, and thereby produce an effect very nearly similar to that due to the curvature; but I prefer to curve it as represented for the reason, among others, that the attendant can better inspect the clasps during their progress.

Instead of withdrawing the supporting-surfaces *i i* by the action of the projections *L L* against the surfaces *L' L'*, as represented, I can allow the lower end of the supporting-piece to strike the die *D* or to strike some other part of the fixed work, and can thereby obtain a greater leverage; but I prefer the device represented, for the reason, among others, that I thereby avoid all danger of cutting or bruising the tapes and hoop-covering.

Some of the advantages due to the several features of my invention may be separately enumerated as follows: First, the india-rubber *N*, arranged as described, makes the concussion on *E* and *e* less violent, and prevents a clasp being thrown out of its right position after it has once acquired it; second, the projections *K K* and corresponding recesses, *K' K'*, (the surface *a* being a part of the boundary of the recesses *K' K'*), by being arranged to oper-

ate the supporting-piece I in the manner represented, compel the supporting-surfaces *i i* to approach to and recede from the hammer *b* at the moment required to properly receive and hold the clasp with the aid simply of a gentle force from the spring *P*, and without a necessity for any complex moving parts to effect the motions; third, the projections *L L* and the corresponding recess *L' L'*, arranged to operate the supporting-piece I in the manner represented, compel the supporting-surfaces *i i* to draw backward out of the way just before the hammer *b* is required to produce its full effect on the clasp and allow the parts to return promptly back to their places by the aid of the spring *P* on the ascent of the hammer *b* without a necessity for any complex moving parts or any liability to cut or injure the work in effecting this operation.

I do not claim any of the parts except in their relation to clasp-sticking machinery, substantially as herein described; but,

Having fully described my invention, what

I claim as new therein, and desire to secure by Letters Patent in machines for securing clasps in hoop-skirts, is as follows:

1. The interposition of a spring, *N*, between the shaker *E e* and the concussive portion of the machine, as represented.
2. The projections *K K* and the recesses *K' K'* and spring *P*, arranged to operate relatively to the supporting-piece *I i*, or its equivalent, substantially as and for the purpose herein set forth.
3. The projections *L L* and the recesses *L' L'* and spring *P*, arranged to operate relatively to the supporting-piece *I i* or its equivalent, substantially as and for the purpose herein set forth.

In testimony whereof I have hereunto set my name in the presence of two subscribing witnesses.

SAMUEL R. WILMOT.
